UNITED STATES PATENT OFFICE.

SETH HOWARD LEAVENWORTH, OF ROCHESTER, NEW YORK, ASSIGNOR TO THE VAN BERGH SILVER PLATE CO., OF ROCHESTER, NEW YORK.

DESIGN FOR A CANDELABRUM.

42,852.

Specification for Design.

Patented Aug. 6, 1912.

Application filed April 10, 1912. Serial No. 689,899. Term of patent 3½ years.

To all whom it may concern:

Be it known that I, SETH HOWARD LEAVENWORTH, a citizen of the United States, residing at Rochester, in the county of Monroe and State of New York, have invented a new, original, and ornamental Design for Candelabra, of which the following is a specification, reference being had to the accompanying drawing, forming part thereof.

The figure is a perspective view of a candelabrum, showing my new design.

I claim:

The ornamental design for a candelabrum, as shown.

SETH HOWARD LEAVENWORTH.

Witnesses:

O. G. ENGLERT,
CLARA J. DORMER.
